UNITED STATES PATENT OFFICE.

ARTHUR F. CASE, OF CLEVELAND, OHIO, ASSIGNOR TO THE WELLMAN-SEAVIER-MORGAN COMPANY, OF CLEVELAND, OHIO, A CORPORATION OF OHIO.

CABLE SUSPENSION FOR HOISTING BUCKETS.

Application filed May 15, 1925. Serial No. 30,491.

This invention relates to a cable suspension for hoisting buckets, carried by an overhead traveling support, and has for its object to provide a cable suspension which 5 will practically eliminate lateral swinging movements of the bucket while the same is being raised and lowered.

In operating the hoisting buckets of the clam-shell type, suspended and operated 10 from an overhead support by means of cables, considerable difficulty has heretofore been experienced in controlling the movements of the bucket due to the fact that the 15 flexibly suspended bucket tends to swing as a pendulum whenever movement of the overhead support in any direction is stopped. For instance when the overhead support is stopped over the hatch of a vessel, the lateral swinging movements of the bucket are apt 20 to cause the same to strike against the sides of the hatch as the bucket is being lowered.

The present invention aims to provide a cable suspension in which certain of the suspension cables are so arranged as to effectively 25 resist pressure tending to move the bucket laterally in any direction, whereby the bucket can be raised or lowered without appreciable swinging movement, due to stopping of the movement of the support.

30 The following description and accompanying drawings set forth in detail certain means embodying the invention, the disclosed means, however, constituting but one of the various mechanical forms in which the principle of the invention may be employed.

Reference should be had to the accompanying drawings forming a part of this specification, in which Fig. 1 is a side elevation showing an overhead supporting structure together with a clam-shell bucket having a cable suspension embodying the present invention; Fig. 2 is an end elevation of the supporting structure showing the drums for operating the equalizer cables and the counterweight for operating these drums; Fig. 3 is a diagrammatic view showing the arrangement of the equalizing and counterweight cables; and Fig. 4 is a fragmentary view showing a slightly different connection between the equalizing and counterweight cables and bucket frame.

Referring to the accompanying drawings, the numeral 1 designates an overhead supporting structure upon which is mounted 55 the hoisting mechanism for operating a flex-

ibly suspended clam-shell bucket 2. The sections of the clam-shell bucket 2 are suspended from a frame 3 in which are housed the bucket opening drums 4, and the holding drum 5. Hoist cables 6 are connected to the holding drums 5 and operating cables 7 are connected to the opening drums 4, the cables 6 and 7 extending vertically from the bucket to the supporting structure. The drums upon which the cables 6 and 7 are wound and the operating mechanism for said drums, are designated generally in Fig. 1 by the numeral 8 and this mechanism may be controlled from an operator's house 9.

The mechanism above described is all old 70 and well-known, the clam-shell bucket and the hoisting and operating means therefor being mechanisms which have been commonly used for many years.

At a suitable point along the length of the overhead support 1, there is journaled a transverse shaft 10 upon which three drums 11, 12 and 13 are fixed, the shaft and drums, as shown herein, being within the operator's house. To the drum 12 is fixed a cable 14 which passes downwardly under a sheave 15 from which a counterweight 16 is suspended and upwardly from the counterweight sheave to a point 17 where it is anchored to the supporting structure 1.

Cables 18 and 19 are attached to the drums 11 and 13 and extend forwardly over guide sheaves 20 carried by the supporting structure 1 and thence downwardly at an inclination to the vertical to the opposite sides of the frame 3 of the bucket adjacent the centers thereof, the cables being attached to the frame 3 by means of shackles 22 and 23. A second pair of cables 24 and 25 are attached, one to the drum 11 and the other to the drum 13, and extend forwardly past the sheaves 20 and 21 to guide sheaves 26 and 27 supported by the structure 1 beyond the opposite end of the bucket frame 3. The cables 24 and 25 extend downwardly at an inclination reverse to that of the cables 18 and 19, and are connected to the frame 3 adjacent to the points of connection of the cables 18 and 19 by means of shackles 28 and 29. The guide sheaves 20 and 21 and also the guide sheaves 26 and 27 are spaced apart a distance greater than the width of the frame 3 of the bucket, so that the cables 18 and 24 are inclined oppositely with respect to the cables 19 and 25. Each of the four cables 18, 19, 24 and 25 110

extends upwardly from the bucket carrying frame and is inclined outwardly in a diagonal direction from its point of attachment to the frame. The action of the counterweight 16 is to wind the cables 18, 19, 24 and 25, upon the drums 11 and 13 and the counterweight 16 acts to keep the said cables at all times under tension and to counterbalance the bucket 2. The inclination of the four cables 18, 19, 24 and 25, is such that lateral movement of the bucket 2 in any direction is resisted and these cables serve to hold the bucket 2 against lateral movements, so that the starting or stopping of the overhead support does not cause the bucket to swing and the bucket can be accurately lowered to the desired spot and positioned at the desired point for discharge. In some instances it may be desirable to connect the cables 18, 19, 24 and 25 to the frame 3, at the corners thereof, instead of midway between the ends as shown in Fig. 4, in which the cables are shown connected at the four corners by shackles 22^a, 23^a, 28^a and 29^a.

Having thus described my invention, I claim:

1. In a device of the character described, a supporting structure, a load carrying member, hoisting means mounted on said structure and including a hoist cable connected to said member, a series of downwardly converging steadyng cables extending from said structure to said load carrying member, drums upon which said cables are wound, and means independent of the hoisting means for simultaneously operating the drums to maintain said cables under tension.
2. In a device of the character described, a supporting structure, a load carrying member, hoisting means including a vertically depending hoist cable extending from said structure to said member, and additional steadyng cables extending from said structure to said member and converging downwardly to the same, and means for automatically paying out and taking up said cables as said member is raised or lowered by said hoisting means.
3. In a device of the character described, a supporting structure, a load carrying member, hoisting means including a vertically depending hoist cable extending from said

structure to said member, and counterbalancing means for said member including a plurality of cables extending from the structure and converging downwardly to said member.

4. In a device of the character described, a supporting structure, a load carrying member, hoisting means of said member mounted on said structure and including a hoist cable connected to said member, a series of steadyng cables extending from the structure to said member, said steadyng cables being inclined with respect to the vertical and arranged to resist lateral movement of the bucket in any direction, and means independent of the hoisting means for simultaneously taking up and paying out said steadyng cables and acting to maintain a uniform tension thereon.

5. In a device of the character described, a supporting structure, a vertically movable hoist bucket, vertically depending hoist and operating cables extending from said structure to said bucket, a series of steadyng cables extending from said structure to the bucket, said steadyng cables each extending from the bucket at an angle to the vertical and each extending laterally from the bucket in a different direction, and means for maintaining said steadyng cables under tension during the raising and lowering of the bucket.

6. In a device of the character described, a supporting structure, a vertically movable hoist bucket, vertically depending hoist and operating cables extending from said structure to said bucket, a series of steadyng cables extending from said structure to the bucket, said steadyng cables each extending from the bucket at an angle to the vertical and each extending laterally from the bucket in a different direction, guide sheaves on said structure over which said steadyng cables pass, a shaft carried by said structure, drums fixed to said shaft, said steadyng cables being wound on said drums, a cable wound on one of said drums in a direction opposite that in which the steadyng cables are wound, and a counterweight supported by said oppositely wound cable.

In testimony whereof, I hereunto affix my signature.

ARTHUR F. CASE.
